UNITED STATES PATENT OFFICE.

HENRY A. STUMPF, OF INDIANAPOLIS, INDIANA.

WASHING-MACHINE.

SPECIFICATION forming part of Letters Patent No. 357,244, dated February 8, 1887.

Application filed July 2, 1885. Serial No. 170,546. (No model.)

To all whom it may concern:

Be it known that I, HENRY A. STUMPF, a resident of Indianapolis, Indiana, have made certain new and useful Improvements in Steam-Washers, a description of which is set forth in the following specification, reference being made to the accompanying drawings, in the several figures of which like letters indicate like parts.

10 My invention relates to an improvement in that class of steam-washers wherein a tank having a suitable cover incloses a drum provided with troughs having central and lateral openings, which revolves upon journals having bearing in the sides of the tank, and will be understood from the following description.

In the drawings, Figure 1 represents a vertical section of my device closed, the handle being indicated in the dotted lines. Fig. 2 20 represents a front view of the wheel, showing its bearings upon the sides of the tank, a portion of the latter being cut away to show the full depth of the wheel, and the cover removed.

25 In detail, *t* is the tank, having handles *h'* and cover *c*, loosely fitting on the top thereof, which has handles *h*.

d is the drum, having stub-axles *a* connected to the sides thereof, which are provided with 30 bearings *b* in the sides of the tank *t*, the drum being revolved by means of power applied to the crank *c r*. The drum is constructed with ribs *r* at suitable distances in the interior thereof, and troughs *tr*, having bottom openings *o*, and lateral openings 1 and 2, this trough being connected to the drum only at the ends, so that the openings 1 and 2 between the ends will be left free for the admission or rejection of the suds. The drum has a cover at the top, 35 hinged at *h*, for opening it to put in the goods designed to be washed.

The device operates as follows: The tank *t*, being partly filled with hot suds, is set upon the stove, the cover of the drum *d* is thrown back, the goods to be washed placed within the drum, the cover shut down and fastened with an ordinary hasp or any suitable catch, and the drum is then revolved in the suds.

The steam and suds enter in through the openings *o*, penetrate the clothes in the drum and 50 saturate them thoroughly, and as the drum is revolved the water inside issues from the opening 1 or 2, according to which way the drum is revolved, it being adapted to revolve in either direction, and the suds will issue 55 from one of these lateral apertures opposite, so that while one receives the other discharges, and a complete circulation is kept up. After the drum with clothes therein has been revolved in one direction for a few minutes, it 60 is well to reverse the movement of the drum and turn it the other way, in order to prevent the clothes from being matted or tangled together.

I am aware that washing-drums having 65 bearings upon the sides of tanks for holding suds are not new, and do not broadly claim the same as my invention; but those heretofore constructed differ from mine in the manner of forming the interior troughs. It will 70 be observed that the sides of my troughs flare in from the periphery of the drum toward the concave bottom of the trough, forming pockets in the corners at their junction for the better carrying of the water, and inlets are provided between the flaring sides and the inner surface of the drum, as shown in the drawings. 75

What I claim as my invention, and desire to secure by Letters Patent, is the following:

In a steam-washer, the drum *d*, provided 80 with a series of troughs, *tr*, whose sides flare inward from the periphery of the drum toward the concave bottom of such trough, such flaring sides and concave bottom forming pockets in the corners at their junction for carrying the water, the bottom of these troughs formed concave and having inlets *o* therein, inlets 1 and 2 being left between such flaring sides and the inner surface of the drum, substantially as described. 85

In witness whereof I have hereunto set my hand this 27th day of June, 1885.

HENRY A. STUMPF.

Witnesses:

C. P. JACOBS,
WM. E. BARTON.
